INVENTOR.

Benjamin S. Phetteplace,

BY

Geo. P. Kimmel.

ATTORNEY.

UNITED STATES PATENT OFFICE.

BENJAMIN S. PHETTEPLACE, OF GREENVILLE, SOUTH CAROLINA.

BUNDLING YARN AND DYEING SAME.

Application filed December 22, 1924. Serial No. 757,439.

To all whom it may concern:

Be it known that I, BENJAMIN S. PHETTEPLACE, a citizen of the United States, residing at Greenville, in the county of Greenville 5 and State of South Carolina, have invented certain new and useful Improvements in Bundling Yarns and Dyeing Same, of which the following is a specification.

This invention relates to a tube or core 10 cover or yarn retainer for use in connection with the dyeing of yarns when wound on compressible or rigid tubes or cores, and has for its object to provide, in a manner as hereinafter set forth, a tube cover or yarn retainer for preventing yarns from falling through the open body of the core or tube when wound on the latter prior to the dyeing of the yarn.

A further object of the invention is to provide, in a manner as hereinafter set forth, a tube or core carrier or yarn retainer capable of being quickly attached in position to envelope the tube or core, and further constructed in a manner as to permit circulation 25 of the dye liquor therethrough, under such conditions not impairing the dyeing action of the yarn bunch wound on the tube or core.

A further object of the invention is to provide, in a manner as hereinafter set forth, a tube or core cover or yarn retainer formed from a flexible perforated sheet of fibrous material to dispense with the employment of the knitted tubular covers now in general 35 use, and in this connection it will be stated that the cover now employed is formed from the knitting of an elongated tube and which is cut to the required length for use. By dispensing with the employment of the knitted tube, and substituting the cover of a flexible perforated sheet of fibrous material, a material saving is had in cost of operation, as it is materially less expensive to construct the cover from the fibrous sheet with 45 respect to the forming of the covers from tubular knitted material.

Further objects of the invention are to provide, in a manner as hereinafter set forth, a tube or core cover or yarn retainer for the purpose referred to which is simple in its construction and arrangement, durable, thoroughly efficient in its use, conveniently applied to the core or tube, and inexpensive to manufacture.

With the foregoing and other objects in

view the invention consists of the novel construction, of tube or core carrier or yarn retainer as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference 65 characters denote corresponding parts throughout the several views:—

Figure 1 is a sectional elevation of a yarn bunch and further illustrating the adaptation of a cover or yarn retainer in connection with a tube or core.

Figure 2 is a an elevation of the cover or yarn retainer.

The cover or yarn retainer can be employed in connection with a compressible or 75 rigid tube or core, and by way of example the tube or core is illustrative of the compressible coiled tube and which is indicated at 1. The tube or core 1 is what may be termed a material holder and carrier for 80 yarn when dyeing the same. The bunch of yarn carried by the tube or core 1 is indicated at 2.

As is well known, it necessitates the employment of a cover for the tube or core 1, 85 to prevent the yarn from falling through the open body portion of the core or tube 1 when the yarn is wound on the latter prior to the dyeing of the yarn. It is also well known that this cover or yarn retainer, as 90 now used is constructed of knitted material in the form of a tube and is mounted on the core, however, the cover or yarn retainer, in accordance with this invention, is formed from a flexible perforated sheet of 95 fibrous material. The sheet, which is indicated at 3, is polygonal in contour and provided with openings 4, which may be of any suitable contour and by way of example, the openings 4 are shown circular. The 100 edges of the sheet 3 are provided with semi-circular notches 5. One marginal portion of one face of the sheet 3, has a coating of adhesive material as indicated at 6, and which is employed for securing the sheet in 105 cylindrical form when the cover is mounted on the tube or core 1. When the sheet 3 is set up to constitute the cover the opposed ends thereof over-lap, as indicated at 7 in

Figure 1.

110

The sheet 3 can be constructed from any suitable fibrous material, such as parchment paper, impervious to moisture, that is to say, a water-proof paper and the sheet may be 5 of the desired length, when the opposed ends thereof are secured together to provide a cylindrical cover, to fit any length or diameter of a compressible or rigid tube or core. It is furthermore to be understood 10 that the sheet 3 can be constructed of any suitable flexible material provided throughout with any shaped perforations and with the opposed ends of the sheet connected together in any suitable manner to provide a 15 cylindrical cover for a compressible or rigid tube or core so that the cover will act as a yarn retainer, to prevent the yarn from falling through the open body of the core or tube and further perforated in such a manner so as not to retard the circulation of the 20 dye liquor during the dyeing operation.

It is thought the many advantages of a cover or yarn retainer, in accordance with this invention can be readily understood and 25 although the preferred embodiment of the invention is as illustrated and described, yet it is to be understood that changes in the detail of construction can be had which will fall within the scope of the invention as 30 claimed.

What I claim is:—

1. A cover or yarn retainer for the purpose set forth consisting of an impervious flexible sheet of fibrous material provided 35 throughout with spaced perforations and having the ends thereof overlapping, the marginal portion of one face at one of said ends provided with an adhesive for securing

said ends together in overlapped position to provide a cover of cylindrical form. 40

2. A cover or yarn retainer for the purpose set forth consisting of an impervious flexible sheet of fibrous material provided throughout with spaced perforations and having the ends thereof overlapping, the 45 marginal portion of one face at one of said ends provided with an adhesive for securing said ends together in overlapped position to provide a cover of cylindrical form, said sheet having each of the edges thereof 50 formed throughout with spaced notches.

3. The combination with an open body core for a yarn bunch, of an impervious sheet of paper completely enveloping said core and having the ends thereof overlapping, said sheet provided throughout with spaced perforations, the marginal portion of one face at one of said ends provided with an adhesive substance for securing said 55 ends together in overlapped position to 60 maintain the cover on the core.

4. The combination with an open body core for a yarn bunch, of an impervious sheet of paper completely enveloping said core and having the ends thereof overlapping, said sheet provided throughout with spaced perforations, the marginal portion of one face at one of said ends provided with an adhesive substance for securing said 65 ends together in overlapped position to 70 maintain the cover on the core, said sheet having each of the edges thereof formed throughout with spaced notches.

In testimony whereof I affix my signature hereto.

BENJAMIN S. PHETTEPLACE.
